UNITED STATES PATENT OFFICE.

JAMES HARTNESS, OF SPRINGFIELD, VERMONT.

CHUCK.

1,193,141.

Specification of Letters Patent.

Patented Aug. 1, 1916.

Application filed April 7, 1915. Serial No. 19,722.

To all whom it may concern:

Be it known that I, JAMES HARTNESS, a citizen of the United States, and a resident of Springfield, in the county of Windsor, and State of Vermont, have invented certain new and useful Improvements in Chucks, of which the following is a specification.

This invention has relation to work holders or chucks for lathes or other like machines.

The object of the invention is to provide a chuck in which the work may be securely held, which will be simple in construction and positive in operation, and in which if desired the jaws may be controlled by a sliding collar similar to that used in controlling clutches.

On the accompanying drawings, Figure 1 represents a chuck embodying the invention, the sliding collar being shown in section. Fig. 2 represents a longitudinal section through the chuck. Fig. 3 represents a view of the front end of the chuck. Fig. 4 represents a view of the opposite end. Fig. 5 represents a transverse section on the line 5—5 of Fig. 2 and shows the rockers in position to close the jaws. Fig. 6 represents a similar section but with the cam in the position to release the jaws. Fig. 7 is an end elevation of the parts in the position shown in Fig. 6. Fig. 8 represents a section on the line 8—8 of Fig. 2. Fig. 9 represents a section through one of the jaws and a supporting rocker, and shows the means for the adjustment of the jaw. Fig. 10 represents the rear face of the jaw and illustrates the thread formed therein. Fig. 11 shows in front or end elevation the chuck body. Fig. 12 represents a section therethrough. Figs. 13 and 14 illustrate the plate for closing the front of the body and assisting in the formation of bearings for the rockers. Fig. 15 shows the cam member for operating the rockers. Fig. 16 shows the quill with the wedge members mounted thereon. Figs. 17 and 18 show detached the member which is carried by the quill. Fig. 19 shows the member which is mounted upon the spindle and also shows in end elevation the spindle and the quill. Fig. 20 illustrates the wedge members at the rear ends of the spindle and quill. Figs. 21 and 22 (Sheet 1) show

a rocker for one of the jaws. Fig. 23 shows one of the jaws detached. Fig. 24 illustrates one of the wedges showing a plan and an edge view of the same. Fig. 25 shows a front end elevation of the chuck, and illustrates how the jaws may be reversed to engage the internal wall of hollow work. Figs. 26 to 28 inclusive illustrate an embodiment of the invention in which the jaw and its supporting rocker are integral. Figs. 29 to 31 inclusive illustrate another embodiment of the invention in which the body is formed separately from and secured to the spindle.

According to the illustrated embodiment of the invention, I provide the chuck body with three rocking jaws having their axes located at the same distance from the axis of the body, and equidistant from each other. These three jaws are so formed that, when they are oscillated in one direction, they are caused to engage the work, and, when they are oscillated in the opposite direction, they release the work. The operative faces of the jaws move in arcs which are tangential to the periphery of the work and a relatively slight rocking movement is sufficient to engage said jaws with or disengage them from the work. Any suitable means may be utilized for oscillating the working jaws, but, in the illustrated embodiment of the invention, I employ a cam member having three cam projections one for each of the jaws, and which, when the cam member is rotated in one direction or the other, impart an oscillatory movement simultaneously to the jaws. I find it convenient and desirable to form or secure the cam member, which may take the form of a ring, upon an internal sleeve or quill which extends rearwardly through the spindle on which the body is formed or secured. For effecting a relative rotative adjustment of the spindle and quill, I preferably employ a wedging mechanism which may be operated by the longitudinal sliding movement of a sleeve, which sliding movement may be secured by the use of the ordinary shipper or handle.

It will be understood that the invention is not limited to the particular details of construction and arrangement of parts which I have illustrated and shall subsequently describe, and that various changes

may be made without departing from the spirit and scope of the invention, as defined by the appended claims.

I will now give a more detailed description of the chuck which is illustrated by Figs. 1 to 25 inclusive of the drawings. The chuck body is indicated as a whole at 30. While it may be formed separately, as afterward explained, I may form it integrally with the spindle 31, which spindle corresponds to that usually employed in metal-turning machines, and which ordinarily is mounted upon suitable bearings afforded by the frame of the machine. The body is comparatively large and rigid. In its front face, it is provided with a recess 32 and with three sockets 33, 33, 33, as shown in Fig. 11, which are radially removed from the axis of the body and which communicate with said recess as best shown in Fig. 12. Arranged in the sockets are the three rockers 34, one of which is shown in detail in Figs. 22 and 23. These rockers are held in place by, and are partially journaled in, a cover plate 35, the front face of which is flush with the front face of the body, as indicated in Fig. 2. This cover plate 35 is shaped as shown in Figs. 13 and 14. In the rear of the cover plate, there is a cam ring 36 which is secured upon a quill or sleeve 37 which extends rearwardly through the spindle. The cam ring is shown as provided with three cam projections 38 which are adapted to engage the cam faces 71 of arms 39 formed on the rockers 34 between their ends. The peripheries of the several rockers are recessed between their ends, as illustrated in Fig. 6, so as to receive the cam projections 38 and also to afford cam faces 40 with which the cam projections may be engaged to move the rockers. By moving the cam ring Fig. 6 clockwise, the cam projections 38 will engage the faces 71 and move the rockers about their respective axes in one direction to cause the engagement of the jaws with the work; and, when said cam ring is moved anti-clockwise, said projections 38 will engage the faces 40 so as to move said rockers in the opposite direction and release the work. Each rocker projects forwardly from the face of the chuck body, as shown in Fig. 2, and it may be provided with an undercut guideway 41 to receive a sliding jaw member 42. Considered broadly, the rocker and the member 42 constitute a rocking jaw, and they may, if desired, be formed in one part or element without capability of relative adjustment. I sometimes herein refer to these parts for convenience as a rocker and a jaw, and to the two together as a rocking jaw or jaw mounted to rock on the body. For convenience, each jaw may be provided with three separate shoulders or faces *a*, *b* and *c* for engagement with the work according to its diameter.

I provide means, however, for adjusting the jaws, said means comprising a worm 43 which engages complementary teeth formed on the rear face of the jaw, as indicated at 44 in Fig. 10. This worm is located in a socket 45 in the front end of the rocker and has a shank 46 with an angular aperture to receive a tool by which it may be rotated. The faces or shoulders *a*, *b* and *c*, by which the work is engaged, may be shaped as shown in Fig. 7, and the jaws are so arranged that, when the rockers are rocked about their axes, the operative portions of the faces may be caused to engage or disengage the work as the case may be, their movement being arcuate and tangential to the periphery of the work or to a circle circumscribed about the axis of the chuck body. The faces are preferably backed off, as shown, being in effect eccentric to the axis of the rocking movement of the jaw, and hence a relatively short rotative movement of the cam ring in one direction or the other is sufficient to cause the jaws to engage or release the work. As shown in Fig. 25, the jaws may be reversed in the rockers, so that their shoulders or faces will engage the inner wall of hollow work.

Any suitable means may be utilized for effecting the relative rotative movement of the cam ring and the chuck body, but I find it convenient to utilize a wedging mechanism operable by a sliding sleeve and including one or more wedges arranged between projections extending radially from the spindle and the quill, as I will now explain. It will be noted from an inspection of Fig. 2 that the rear end of the quill 37 projects a short distance beyond the end of the spindle 31. For convenience of manufacture, to these two members are secured collars provided with the radial projections between which are located one or more wedges, the latter being moved in the direction of the axis of the spindle by said sleeve so as to force the spindle and the quill rotatively in opposite directions. The collar for the spindle is indicated at 50 and it is keyed thereto as indicated at 51. The collar for the quill is indicated at 52 and it is keyed upon the quill as indicated at 53, being held in place by the threaded sleeve 54. Said collar 50 has two radial projections 55, 55, and the collar 52 has two radial projections 56, 56. These latter projections 56 are formed on lugs 57 which project forwardly from the collar 52 as shown in Figs. 16, 17 and 18. The projections 56 and 57 lie in the same transverse planes of the spindle as shown in Fig. 20. Between these projections 55 and 56 may be arranged the four wedges 58, two having their smaller ends projecting forwardly and the alternating wedges having their smaller ends projecting rearwardly. One of these wedges is

illustrated in Fig. 24. Said wedges rest upon the peripheral portions of the two collars between the radial projections formed thereon respectively, and they are encircled by a sleeve 60 which has peripheral ribs or flanges 61, 62, forming a groove to receive the usual rolls or blocks or collar carried by the usual shipping lever. On both ends of each wedge are flanges 59 which overlap the ends of the sleeve 60, so that, notwithstanding the sleeve may rotate relatively thereto, yet, when the sleeve is moved in one direction or the other, the wedges will be carried with it. From this explanation, it will be quite clear that, when the wedges are moved axially of the spindle in one direction or the other, their sliding engagement with the radial projections 55, 56 of the two collars 50 and 52 will effect a relative rotative adjustment of the spindle and quill, and that this movement will be positive irrespective of whether the sleeve be moved forwardly or rearwardly. Thus there is present in this device a member which is movable longitudinally of the chuck axis and which through intervening mechanism effects a rocking movement, or opening and closing of the jaws.

In Figs. 26 to 28 inclusive, I have illustrated a form of the invention in which the jaws and the rockers are integral. The jaws are indicated at 70, and their shanks which constitute the rockers are indicated at 71 and are slightly reduced in diameter. These shanks are grooved at 72 to receive the cam projections 38 of the cam member 36, the bottom walls of the grooves being curved or otherwise formed to constitute cam faces to be engaged by the projections 38, so that the jaws will be rocked when the cam member is moved about its axis. The location of the cam projections 38 in the grooves 72 prevents the endwise dislocation or removal of the rockers from the chuck body. But, by rotating the cam member to an abnormal position, as shown in Fig. 28, the jaws and their rockers may be withdrawn from the body. In this form of the invention, each of the jaws has but a single shoulder or face 73 which is slightly concave, and which is rounded at the ends.

I have already stated herein that the chuck body may be formed separately from the spindle. In Figs. 29 to 31, I have shown such a construction. The spindle 80 has at its front end a flange 81 to which the body 82 is secured by screws 83. The cam member 84 is journaled in three blocks or projections 85 projecting forwardly from the body 82 and lying between the projections 86 of said cam member. This cam member is made of three parts or segments as shown in Fig. 31, and they are engaged with ribs 87 formed on the quill 88. They are inserted in the body and then the quill is passed through the body, the head 89 of said quill holding them in place. Instead of having an inner ring or cover plate, as in the first form of chuck, I employ an outer cover plate 90, which is socketed at 91 to 70 coöperate with the body to form bearings for the rocking jaws. This plate is secured in place by screws 92 and it is flush with the front faces of the blocks or projections 85 and also with the end of the quill. 75

In the forms of chuck shown in Figs. 26 to 31 inclusive, the quill and the spindle may be rotatively adjusted, one relatively to the other, by wedging mechanism such as described in connection with the chuck 80 shown in Figs. 1 to 24 inclusive.

Having thus explained the nature of my said invention and explained a way of making and using the same, although without attempting to set forth all of the forms in 85 which it may be made or all of the modes of its use, what I claim is:—

1. A chuck comprising a recessed body, a plurality of jaws mounted in the recesses in said body to rock on axes parallel to the axis 90 of said body, and a member concentric with the body and axially immovable relatively thereto, and having cam members thereon for operatively engaging said jaws to rock them. 95

2. A chuck comprising a recessed body, a plurality of rockers mounted in the recesses of the body to rock on axes parallel to the axis of said body, jaws on the ends of said rockers having work-engaging faces located 100 in front of said body, and means for actuating the rockers including an annular cam directly engaging said rockers and held against axial movement relatively to said body, said annular member being arranged 105 concentrically within said body, and means for moving said cam about its axis.

3. A chuck comprising a body, a plurality of jaws mounted on said body to rock on axes parallel to the axis of said body, and 110 a cam arranged concentrically with said body and held against axial movement relatively thereto, said cam and jaws having co-operative engaging portions, in consequence of which the rotation of said cam imparts 115 a rocking movement to said jaws.

4. A chuck comprising a body, jaws mounted on said body to rock on axes parallel with the axis of said body, said jaws having cam faces, a cam concentric with 120 said body and arranged to engage said faces, means for holding said cam against axial movement relatively to said body and said jaws, and means for effecting a relative rotative movement of said cam and said body. 125

5. A chuck comprising a body having sockets radially removed from the axis thereof, rocking jaws journaled in said sockets and having work-engaging portions projected beyond the front face of said 130

body, and means within the body for operatively engaging said jaws to rock them, including an axially immovable sleeve and external members thereon for operating said jaws.

- 5 6. A chuck comprising a body, rockers mounted thereon to move about axes parallel to the axis of the body, and having their ends projecting beyond the front face 10 of the body, a jaw supported on the projecting end of each rocker and adapted to slide transversely thereof in lines intersecting the axis thereof, means for slidably adjusting said jaws independently of each 15 other, and means for rotating said rockers on their respective axes simultaneously to cause the jaws to engage or release the work.

7. A chuck comprising a body, rocking jaws mounted thereon to rock on axes radially removed from the axis of said body, a cam member for rocking said jaws in unison, means for holding said cam member against axial movement relatively to said 20 body and said jaws, and wedging mechanism for effecting a relative rotative movement of said cam member and said body.

8. In combination, a work spindle, a chuck body thereon, rocking jaws on the 25 chuck body mounted to rock on axes radially removed from the axis of said body, an oscillatory quill or sleeve concentric with said spindle and axially immovable relatively thereto, means operatively connected 30 with said quill to rock said jaws, and means for effecting a relative rotative movement of said spindle and quill.

9. In combination, a work spindle, a chuck body thereon, rocking jaws on the 35 chuck body mounted to rock on axes radially removed from the axis of said body, a quill or sleeve within and concentric with said spindle, means operatively connected with said quill to rock said jaws, one or 40 more wedges constructed and arranged to effect a relative rotative movement of the spindle and quill, and means for moving said wedge or wedges relatively to said spindle and sleeve lengthwise thereof.

50 10. In combination, a work spindle, a chuck body thereon, rocking jaws on the chuck body mounted to rock on axes radially removed from the axis of said body, a quill or sleeve within said spindle and held against 55 axial movement relatively thereto, means operatively connected with said quill to rock said jaws, said spindle and quill having radial projections, and one or more wedges between said projections and movable axial 60 ally of the spindle to effect a relative rotative movement of the spindle and quill.

11. In combination, a work spindle, a chuck body thereon, rocking jaws on the chuck body mounted to rock on axes radially 65 removed from the axis of said body, a

quill or sleeve within said spindle, means operatively connected with said quill to rock said jaws, said spindle and quill having radial projections, one or more wedges between said projections and movable axially 70 of the spindle to effect a relative rotative movement of the spindle and quill, and a sliding sleeve operatively connected with said wedges to move them.

12. In combination, a hollow work spindle, 75 a chuck body at one end thereof, rocking jaws carried by said body, a sleeve mounted to slide on the other end of said spindle, and mechanism actuated by said sleeve and extending through said hollow 80 spindle for rocking said jaws to engage or release the work.

13. In combination, a work spindle, a chuck body thereon having movable jaws, a sleeve mounted to slide axially of said spindle, and means actuated by said sleeve for moving said jaws to engage or release the work, said means comprising a quill within 85 said spindle and held against longitudinal movement relatively thereto, and one or more wedges operatively connected with said sleeve and arranged by a wedging action 90 to effect a relative rotative movement of said quill and spindle.

14. In combination, a chuck body, movable jaws thereon, a rotatable quill having means for actuating said jaws to engage and release the work, a spindle connected to said body, said spindle and quill having radial projections and being held against 95 relative longitudinal movement, a wedge movable longitudinally of the spindle and the quill and engaged with said projections, and means for moving said wedge to separate said projections and thus effect a relative rotative movement of the spindle and quill.

15. In combination, a chuck body, rockers mounted thereon to move on axes parallel to the axis of the chuck body and having transverse guideways on the ends thereof, means for oscillating said rockers simultaneously, reversible jaws mounted on said rockers to slide in said guideways transversely to the axes of said rockers, and adapted for gripping the interior or the exterior walls of the work, and means for adjusting said jaws in said guideways in lines transverse to the axes of said rockers.

16. A chuck comprising a centrally apertured chuck body having parallel recesses radially removed from and parallel to the axis thereof, rockers mounted in said recesses, a front plate secured to said body, jaws on said rockers located outside of said front plate, a centrally disposed cam held against axial movement relatively to said body and said rockers for rocking said rockers, and means for imparting a rotative movement to said cam in either direction.

17. A chuck comprising a hollow spindle and a centrally apertured body on the end thereof, a quill extending through said spindle into the chuck body and having cam members thereon, means for holding said quill and cam members against axial movement relatively to said spindle and said body, rocking jaws journaled in sockets in the jaw body radially disposed from the axis thereof and each having faces adapted to be alternately engaged by one of the cam members whereby the jaw is rocked or oscillated in one direction or the other, and means for rotatively moving said quill and cam members alternately in opposite directions.

18. A chuck comprising a body, parallel rockers journaled in sockets formed in said body parallel with but removed from the axis thereof, a rotatable cam for rocking said rockers and held against axial movement relatively thereto, and jaws on the

ends of said rockers, each of said jaws having a flat work engaging face tangential to a circle circumscribed about the axis of 25 the associated rocker.

19. In a chuck, the combination with a body, a spindle, and jaws mounted on said body, of mechanism for actuating said jaws comprising a sleeve immovable axially of 30 said spindle, projections on said spindle and said sleeve, oppositely arranged wedges lying between said projections, and an encircling collar engaged with said wedges and movable axially of the spindle and the 35 sleeve to move said wedges relatively to said projections to effect a relative rotative movement of said spindle and said sleeve.

In testimony whereof I have affixed my signature, in presence of two witnesses.

JAMES HARTNESS.
